[54]	PROCESS FOR THE PRODUCTION OF AN ANTIBIOTIC SUBSTANCE 2'-AMINO-2'-DEOXY- KANAMYCIN IN HIGHER YIELD 1 Claim, 2 Drawing Figs.		
[52] U.S. Cl.	195/80		

ABSTRACT: This invention relates to processes for the production of an antibiotic substance 2'-amino-2'-deoxy-kanamycin in higher yield. More particularly, this invention relates to the processes for the production of 2'-amino-2'-deoxy-kanamycin by fermentation using mutants of *Streptomyces kanamyceticus* identified as ATCC21259, ATCC21260, ATCC21161 and ATCC21268.

FIG. 2

**PROCESS FOR THE PRODUCTION OF AN ANTIBIOTIC
SUBSTANCE 2'-AMINO-2'-DEOXY-KANAMYCIN IN
HIGHER YIELD**

2'-Amino-2'-deoxy-kanamycin is effective in inhibiting the growth of Gram-positive, Gram-negative and acid-fast bacteria such as *Staphylococcus*, *Pseudomonas*, *Salmonella*, *Shigella* and *Mycobacterium* as well as pathogenic bacteria which are resistant to the known antibiotics and synthetic chemotherapeutic agents. This 2'-amino-2'-deoxy-kanamycin is substantially of very much low toxicity and particularly of little ototoxicity, and it exhibits a useful therapeutic effect on the infections of Gram-positive, Gram-negative and acid-fast bacteria in human beings and animals.

2'-Amino-2'-deoxy-kanamycin has the empirical formula $C_{18}H_{37}N_5O_{10}H_2O$ and may be represented by the structural formula:

In investigating the commercial production of kanamycin A by the fermentation, we have, found that the known natural strains such as strain 0-4-1 of *Streptomyces kanamyceticus* which have been used up to now for the commercial production of kanamycin A usually can produce and accumulate kanamycin A in a very much larger amount than 2'-amino-2'-deoxy-kanamycin in the culture.

As result of our further investigations, we have found that the proportion of 2'-amino-2'-deoxy-kanamycin produced and accumulated in the culture may be improved remarkably and may be recovered therefrom in higher yield when some new mutants of *Streptomyces kanamyceticus* are cultured in the known manner using an ordinary culture medium which are conventionally employed for the cultivation. Thus, we have further discovered that some new mutants of *Streptomyces kanamyceticus* which we have now derived from a typical natural strain 0-4-1 of *Streptomyces kanamyceticus* can exhibit a higher ability to produce 2'-amino-2'-deoxy-kanamycin than the parent natural strain 0-4-1, when they are cultivated in the known culture medium.

These new mutants having intrinsically the greater capability to produce 2'-amino-2'-deoxy-kanamycin have been obtained by treating the known, natural strain 0-4-1 of *Streptomyces kanamyceticus* with a mutation agent, namely nitrogen mustard or irradiation of ultraviolet rays and subjecting the surviving mycelia or spores to special screening.

These new mutants which intrinsically have the greater capability to produce 2'-amino-2'-deoxy-kanamycin include four types of mutants which have been given the laboratory designations A-4-6, 3AG, 18-8 and 19-2, respectively. These new mutants each have little or no ability to utilize xylose, and they are distinguishable from the parent strain 0-4-1 which has a greater capability to utilize xylose.

Variation or mutation of *Streptomyces kanamyceticus* is naturally expected since such is a common property of an actinomycete. Therefore, when any known strain of *Streptomyces kanamyceticus* is treated with a known mutation agent such as nitrogen mustard, it may be expected that, in addition to the above-mentioned mutants A-4-6, 3AG, 18-8 and 19-2, there are obtained other mutants which intrinsically exhibit the greater capability to produce 2'-amino-2'-deoxy-kanamycin.

According to the present invention, therefore, we provide a process for the production of 2'-amino-2'-deoxy-kanamycin in higher yield, which comprises cultivating a mutant of *Streptomyces kanamyceticus* which intrinsically exhibits the greater capability to produce 2'-amino-2'-deoxy-kanamycin, under aerobic conditions in a usual culture medium containing the ordinary carbon sources and nitrogen sources, until 2'-amino-2'-deoxy-kanamycin accumulates in a significant amount in the culture, and then recovering said antibiotic from the culture.

As embodiments of the process of the present invention, there are also provided a process for the production of 2'-amino-2'-deoxy-kanamycin in a higher yield, which comprises cultivating the mutant A-4-6, 3AG, 18-8 or 19-2 of *Streptomyces kanamyceticus* under aerobic conditions in a usual culture medium containing carbohydrate and nitrogenous nutrient until the 2'-amino-2'-deoxy-kanamycin accumulates in a significant amount in the culture, and then recovering said antibiotic from the culture.

In the process of the present invention, the cultivation may generally be carried out in the usual manner as in the ordinary methods of cultivating the known actinomycetes. The culture medium containing known kinds of nutritional sources for actinomycetes are useful for the production of 2'-amino-2'-deoxy-kanamycin. Thus, the culture medium may contain the sources of carbon such as starch, sucrose, maltose, glucose and glycerol etc. and the sources of nitrogen such as soybean meal, soluble vegetable proteins, corn steep liquor, peptone, meat extract, nitrates and ammonium salts. The culture medium may also contain other appropriate inorganic salts such as $NaCl$, $MgSO_4$ and such a material which will promote the growth of *Streptomyces kanamyceticus*, if necessary.

For the production of 2'-amino-2'-deoxy-kanamycin, the cultivation on solid medium is possible, but for the production in large quantity it is better to carry out the cultivation in a liquid medium under aerobic conditions. For the production of the antibiotic on a large scale it is much more preferable to employ a method of deep aerated submerged cultivation. It is possible to use the shake-cultivation and the aerated agitated cultivation in a liquid medium. The cultivation temperature usually may be between 25° and 35° C. and preferably at a temperature of 28° C. or in the vicinity thereof. It has been found that the amount of 2'-amino-2'-deoxy-kanamycin accumulating in the culture becomes maximum at the end of 3 to 7 days after the beginning of the cultivation.

2'-Amino-2'-deoxy-kanamycin which has accumulated in the culture may be recovered therefrom by any one of the known method of using ion-exchange resins, the method of extracting with organic solvents and the method of using a precipitating agent which are usually employed for the purification of the known water-soluble, basic antibiotics. For the commercial production of 2'-amino-2'-deoxy-kanamycin, it is preferred to recover this by a method of adsorption and elution with an ion exchanger, preferably carboxylic acid type cation-exchange resin, or by a method of extraction with an organic solvent containing an appropriate carrier such as paratoluene sulfonic acid or lauric acid. For instance, 2'-amino-2'-deoxy-kanamycin may be recovered by filtering off the solids such as mycelium cake from the fermented broth containing 2'-amino-2'-deoxy-kanamycin, subjecting the filtrate to an adsorption treatment with Amberlite IRC-50 (a registered Trade Name of an ion-exchange resin as produced by Rohm & Haas Co., U.S.A.), eluting with aqueous ammonia, collecting and concentrating the active fractions, subjecting the concentrated fraction to chromatographic separation with Dowex 1×2 (a registered Trade Name of an ion-exchange resin as produced by Dow Chemical Co., U.S.A.), collecting and concentrating the active fractions. The concentrated fraction is again subjected to a chromatographic separation by adsorbing on Amberlite CG-50 and gradient eluting with water-aqueous ammonia. A single fraction containing an active compound, that is, 2'-amino-2'-deoxy-kanamycin may be obtained. This fraction is freeze-dried and the resulting powder is

crystallized from water-dimethyl formamide to yield the crystals of 2'-amino-2'-deoxy-kanamycin.

2'-Amino-2'-deoxy-kanamycin may be obtained in the form of colorless needlelike crystals having a melting point of 183°-186° C. basic and soluble in water, aqueous methanol, aqueous ethanol, aqueous acetone but insoluble in absolute methanol, absolute ethanol, ethyl acetate, butyl acetate, ethyl ether, chloroform and benzene, giving positive reaction to ninhydrin, Elson-Morgan and Molisch reagents but negative reaction to Sakaguchi, Tollens, Fehling, Millon and Benedict reagents, and an aqueous 1 percent solution of this substance shows a specific rotation $[\alpha]_D^{21} = +118^\circ$. An N-acetyltaate obtained by acetylating 2'-amino-2'-deoxy-kanamycin with methanol-acetic anhydride has the empirical formula $C_{18}H_{32}N_5O_{10}S(CH_3CO)H_2O$, melts at 290°-300° C. with decomposition and gives a specific rotation $[\alpha]_D^{21} = +118^\circ$.

The antibacterial activity of 2'-amino-2'-deoxy-kanamycin is heat stable. When a solution of the 2'-amino-2'-deoxy-kanamycin in 6N-hydrochloric acid has been degraded by heating at 100°C. for 40 minutes, the antibacterial activity against *Bacillus subtilis* of the degraded solution retained 60-80 of the initial potency of the solution. The degraded solution is applied in the form of a spot on a sheet of 40 cm. $\times$ 40 cm. of Toyo filter paper No. 50 and then developed upwards with a solvent consisting of butanol-acetic acid-water (4:2:1). This paper chromatography shows that there occur two spots which give a positive reaction to ninhydrin and that one of the spots is also positive in the reaction to ammoniac silver nitrate.

2'-Amino-2'-deoxy-kanamycin exhibits high and useful antibacterial activity against Gram-positive, Gram-negative and acid-fast bacteria as well as against such bacteria and strains which are resistant to kanamycin A, other known antibiotics and chemotherapeutic agents. Toxicity of 2'-amino-2'-deoxy-kanamycin is very low, as its LD_{50} is only 190 mg./kg. in mice (intravenous injection).

Antibacterial spectrum of 2'-amino-2'-deoxy-kanamycin is tabulated in table 1 below.

15 In the attached drawings:

FIG. 1 shows a curve of the ultraviolet absorption spectrum of 2'-amino-2'-deoxy-kanamycin dissolved in water at a concentration of 1 mg./ml. of water.

20 FIG. 2 shows a curve of the infrared absorption spectrum of 2'-amino-2'-deoxy-kanamycin in Nujol.

25 Referring to FIGS. 1 and 2, it is noted that 2'-amino-2'-deoxy-kanamycin does not exhibit absorption of ultraviolet light from 220 milimicrons to 340 milimicrons but exhibits characteristic absorption bands at the following wave numbers in cm.⁻¹, 3,600, 3,000, 1,650, 1,600, 1,570, 1,140, 1,110, 1,095, 1,090, 1,060, 1,035, 960, 900, 895, 880, 845, 815, 790, 780, 765, and 725.

30 A culture of the parent strain 0-4-1 of *Streptomyces kanamyceticus* has been deposited in the A.T.C.C. in Washington, D.C., and added to its permanent collection of micro-organisms as the deposition No. 21252. Furthermore, cultures of the mutants A-4-6, 3AG, 18-8 and 19-2 of *Streptomyces kanamyceticus* which may be used in carrying out the process of the second aspect of the present invention also have been deposited in the A.T.C.C. as the deposition Nos. 21260, 21259, 21261 and 21268 respectively.

35 As stated hereinbefore, the mutants A-4-6, 3AG, 18-8 and 19-2 of *Streptomyces kanamyceticus* are characterized by having little or no ability to utilize xylose, as compared to the high xylose-utilizing ability of their parent strain 0-4-1.

40 The mutant A-4-6 is further characterized in that it does not grow on sucrose-Czapek-agar plate containing no deoxystreptamine whereas the parent strain 0-4-1 do. The mutant 3AG is further characterized in that it forms considerably larger colonies on a Czapek-agar plate containing 3-amino-glucose than the parent strain 0-4-1. The mutants 18-8 and 19-2 used according to the present invention are further characterized in that they do not or little utilize dulcitol whereas the parent strain 0-4-1 has a very much higher ability to utilize dulcitol.

45 These mutants were produced by using the following method of mutation and screening. The procedures of obtaining each of the mutants A-4-6, 3AG, 18-8 and 19-2 are described below in more detail.

50 The mutant A-4-6 was produced by treating the typical strain 0-4-1 of *Streptomyces kanamyceticus* as follows: the aforesaid typical strain of *Streptomyces kanamyceticus* was inoculated to the surface of a slant of sucrose-Czapek-agar which was then incubated at 28° C. for 7 days. A platinum-loop amount of the resulting culture was separated therefrom and inoculated to 10 ml. of a liquid medium containing 1 percent corn steep liquor and 0.25 percent dried yeast at pH of 7.0 in a 70 ml. test tube. Shaken cultivation was carried out at 28° C. for 24 hours on a reciprocating shaker which reciprocated at 350 cycles per minute with amplitude of 2 cm. The growing mycelia so obtained were isolated by centrifuging the culture broth for 10 minutes under gravity of 2,000 g. and discarding the supernatant liquid. The mycelium cake was washed twice with equal amounts of 0.9 percent physiological

55 saline solution and the obtained wet mycelia were suspended in the 0.9 percent physiological saline solution to the volume of 5 ml. to which 4 ml. of a solution containing one-fourth mol. of Na_2HPO_4 was added, then the mixture was added with 1 ml. of a solution of 500 mcg./ml. of the nitrogen mustard, and allowed to stand for 10 minutes. Subsequently, 1 ml. of

the resulting mixture was taken into 9 ml. of a neutralizing solution of 0.2 percent glycine and 0.17 percent NaHCO_3 , and the mixture was allowed to stand at room temperature for about 1 hour. The mycelium cake was isolated therefrom by centrifuge, rinsed and then the whole amount of the mycelia was transplanted into 10 ml. of corn steep liquor medium in a 70 ml. test tube. Shaken cultivation was then performed at 28° C. for 24 hours in the same way as mentioned above. The culture was rinsed twice, diluted and then inoculated to sucrose-Czapek-agar plate which further contained 100 mcg./ml. of deoxystreptamine added. Incubation was made at 28° C. for 10 days to give colonies.

Some amounts of mycelia were removed removed from each of the colonies and seeded to 10 ml. of corn steep liquor medium in a 70 ml. test tube. Shaken cultivation was again carried out at 28° C. for 24 hours in the same way as mentioned above. The resulting culture was twice rinsed, diluted and then inoculated to sucrose-Czapek-agar plate and sucrose-Czapek-agar plate which additionally contained 100 mcg./ml. of deoxystreptamine. Incubation was made at 28° C. for 7 days to give colonies. Such a strain which did not grow in the former plate but grew only in the latter plate was isolated and designated as the mutant A-4-6 of *Streptomyces kanamyceticus*. This mutant which exhibited essential demand for deoxystreptamine was found to be present at a ratio of about one colony to 100 colonies which were formed.

The mutant 3AG was produced by treating the parent strain 0-4- as follows: a culture of the typical strain 0-4-1 of *Streptomyces kanamyceticus* was inoculated on the surface of a slant of sucrose-Czapek-agar and incubated at 28° C. for 7 days. A platinum-loop amount of the resulting culture was removed therefrom and transplanted in 10 ml. of a liquid medium containing 1 percent corn steep liquor and 0.25 percent dried yeast at pH 7.0 in a 70 ml. test tube. Shaken cultivation was made at 28° C. for 24 hours on a reciprocating shaker which reciprocated at 350 cycles per minutes with an amplitude of 2 cm. The culture was washed twice with physiological saline solution and then treated with a solution of 50 mcg./ml. of the nitrogen mustard. Mycelia of the strain so treated were then inoculated to 3-amino-glucose-containing Czapek medium which contained 3 percent of 3-amino-glucose in place of 3 percent of sucrose, and shaken cultivation was then made at 28° C. for 24 hours in the same way as mentioned above. From the culture were separated by centrifuging the growing mycelia which were then inoculated to corn steep liquor medium for the purpose of improving the growth thereof. Shaken cultivation was made again at 28° C. for 24 hours in the same way as mentioned above. After the culture was washed, the resulting suspension was homogenized, diluted and then inoculated to 3-amino-glucose-Czapek-agar plate which was subsequently incubated at 28° C. for 14 days to form the colonies. As result, there were formed small-sized colonies, mediate-sized colonies and large-sized colonies. Mycelia were separated only from the large-sized colonies and then inoculated to corn steep liquor medium. Shaken cultivation was carried out again at 28° C. for 24 hours in the same way as mentioned above. After washing, the suspension was homogenized, diluted and then inoculated to 3-amino-glucose-Czapek-agar plate, which was further incubated at 28° C. for 14 days to form colonies again. As result, such a strain which formed only large-sized colonies was isolated and

designated as mutant 3AG of *Streptomyces kanamyceticus*. The mutants 18-8 and 19-2 were produced by treating the parent strain 0-4-1 as follows: a culture of the parent strain 0-4- of *Streptomyces kanamyceticus* was inoculated to the surface of a slant of starch-Czapek-agar and incubated at 28° C. for 7 days. A platinum-loop amount of the resulting culture was removed therefrom and suspended in 1 ml. of sterilized water. After the suspension was triturated, it was transplanted in a dish containing starch-Czapek-agar and then incubated at 28° C. for 10 days.

After the incubation, the dish was placed below an ultraviolet lamp (19watt sterilization lamp as produced by Toshiba Co., Japan) and then irradiated with ultraviolet rays for 10 minutes with keeping a distance of 30 cm. between the dish and lamp. After this mutation treatment, the mycelia on the agar surface were scraped up and suspended in 10 ml. of sterilized water. The suspension was homogenized and then applied onto a starch-dulcitol-Czapek-agar (that is a Czapek-agar containing 0.1 percent starch and 3 percent dulcitol) and incubated at 28° C. for 7 days. Mycelia were separated only from the small-sized colonies which slightly had grown on the agar. The mycelia were then inoculated to starch-Czapek-agar slants and incubated at 28° C. for 7 days. On these starch-Czapek-agar slants, all the colonies showed good growth. Platinum-loop amounts of mycelia were separated from each of the slants and then inoculated to dulcitol mineral agar slant (containing 1 percent dulcitol, 0.264 percent ammonium sulfate, 0.565 percent di-potassium hydrogen phosphate, 0.238 percent mono-potassium di-hydrogen phosphate, 0.1 percent magnesium sulfate hepta-hydrate, 0.00064 percent cupric sulfate penta-hydrate, 0.00079 percent manganese chloride tetra-hydrate, 0.00011 percent ferric sulfate hepta-hydrate, 0.00015 percent zinc sulfate hepta-hydrate and 1.5 percent agar, pH 7.0). Incubation at 28° C. for 14 days gave a predominant number of strains which showed the normal growth as well as only two strains which could not grow significantly. These two strains which could grow on the starch-Czapek-agar but could not grow on the dulcitol mineral agar have been found to exhibit the ability to produce 2'-amino-2'-deoxy-kanamycin at higher efficiency, and these mutants have been designated as mutants 18-8 and 19-2 of *Streptomyces kanamyceticus*, respectively.

The mutants Nos. 3AG, A-4-6 18-8 and 19-2 of *Streptomyces kanamyceticus* used according to the present invention have the following characteristics. These mutants Nos. 3AG, A-4-6, 18-8 and 19-2 are morphologically similar to each other in that the aerial mycelia make branches but not comparatively fine and usually do not produce spiral and whorl that spores are formed at the tips of aerial mycelia and are usually of an oval or cylindrical shape of generally 1.0 to 1.5 microns in width and that the surface of the spores is smooth. However, they are distinguishable from each other with respect to their conditions of the growth on culture media, their physiological actions and their ability to utilize carbon sources. The conditions of the growth, physiological actions and utilization of carbon sources of these mutants of *Streptomyces kanamyceticus* are summarized in tables 2, 3 and 4 below. Moreover, the differences between the typical strain 0-4- of *Streptomyces kanamyceticus* and the mutants Nos. A-4-6, 3AG 18-8 and 19-2 derived therefrom are summarized in table 4 hereinafter, with respect to their growth conditions, physiological actions and utilization of carbon sources.

TABLE 4.—DIFFERENCES BETWEEN THE TYPICAL STRAIN 0-4-1 AND THE MUTANTS OF *STREPTOMYCES KANAMYCETICUS*

Observations	<i>S. kanamyceticus</i>				
	Strain 0-4-1	Mutant No. A-4-6	Mutant No. 3AG	Mutant No. 18-8	Mutant No. 19-2
Growth on:					
Sucrose Czapek agar plate	+++	±	++	+	+
Dextrosestreptamine Czapek agar plate	±	+	±	±	
3-aminoglucose Czapek agar plate	+	—	+++	±	
Dulcitol Czapek agar plate	+++	+++	++	±	±
Potato plug	(1)	(2)	(3)	(3)	(3)
Physiological action:					
Liquefaction of gelatin	+	++	+	+	+
In skimmed milk medium	(4)	(3)	(3)	(4)	(4)
Utilization of carbon sources:					
Sucrose	+++	±	++	+	+
Xylose	++	—	—	±	±
Sodium acetate	++	—	±	+++	+
Sodium citrate	+++	+	++	+	+
Sodium succinate	++	±	++	+	+
Dulcitol	+++	++	+++	±	±

1 Wrinkled growth, granular surface, lightly brown colored.

2 Elevated good growth, ochre colored.

3 Wrinkled growth, granular surface, faint yellowish brown colored.

4 Slow peptonization.

5 Rapid peptonization.

EXAMPLE 1

A liquid culture medium (15 l.) containing 3.0 percent maltose, 2.0 percent starch, 3.0 percent soybean meal, 1.0 percent sodium nitrate and 0.5 percent sodium chloride was inoculated with the mutant No. A-4-6 of *Streptomyces kanamyceticus* and then incubated at 28° C. under aeration and agitation. The quantity of 2'-amino-2'-deoxy-kanamycin accumulating in the culture reached maximum at the end of 6 days of the incubation.

The culture broth was then filtered to give 14 l. of the filtrate which was then treated with 4 l. of Amberlite IRC-50 (ammonium type). The resin was subsequently eluted with 0.5 N aqueous ammonia. The active fractions were collected and concentrated to a syrup which was then dissolved in 500 ml. of water. The solution was decolorized by treating with 6 g. of active carbon. The solution was filtered to remove the carbon, and the filtrate was subjected to chromatographic elution with 600 ml. of Dowex 1×2 (OH type). 2'-Amino-2'-deoxy-kanamycin was eluted out before the separation of kanamycin A. The fractions containing high concentration of 2'-amino-2'-deoxy-kanamycin were collected, concentrated and freeze-dried to give 3.2 g. of a crude powder. This crude powder was dissolved in 50 ml. of water and the solution was treated with a resin Amberlite CG-50 (ammonium type) to adsorb the antibiotics. The resin was again subjected to chromatographic elution with 0.1 N to 0.5 N aqueous ammonia. The coexisting small amount of kanamycin A was then eluted out at first and 2'-amino-2'-deoxy-kanamycin was subsequently eluted separately as a single fraction. This single fraction was concentrated and freeze-dried to give a crude powder of 2'-amino-2'-deoxy-kanamycin. Recrystallization of this powder from water-dimethyl-formamide gave 1.9 g. of 2'-amino-2'-deoxy-kanamycin in the form of colorless, needlelike crystals.

EXAMPLE 2

A liquid culture medium (15 l.) having the same composition as in example 1 was inoculated with the mutant No. 3AG of *Streptomyces kanamyceticus* and then incubated at 28° C. under aeration and agitation. The quantity of 2'-amino-2'-deoxy-kanamycin accumulating in the culture reached maximum at the end of 6 days of incubation.

The culture liquid was then treated in the same procedures as in example 1 to give 1.2 g. of a crystalline form of 2'-amino-2'-deoxy-kanamycin.

EXAMPLE 3

A liquid culture medium (15 l.) having the same composition as in example 1 was inoculated with the mutant No. 18-8 of *Streptomyces kanamyceticus* and then incubated at 28° C. under aeration and agitation. The quantity of 2'-amino-2'-deoxy-kanamycin accumulating in the culture reached maximum at the end of 6 days of incubation.

imum at the end of 7 days of incubation.

The culture liquid was then treated in the same procedures as in example 1 to give about 2.2 g. of a crystalline form of 2'-amino-2'-deoxy-kanamycin.

EXAMPLE 4

The procedure of example 1 was repeated using the mutant No. 19-2 of *Streptomyces kanamyceticus*. A similar result was obtained to that of example 1. 3.15 g. of 2'-amino-2'-deoxy-kanamycin was obtained in a crystalline form.

EXAMPLE 5 (comparative)

In this example, a series of tests was carried out in order to demonstrate the unexpected and advantageous effect of using the mutants A-4-6, 3AG, 18-8 and 19-2 which intrinsically have the higher ability to produce 2'-amino-2'-deoxy-kanamycin, on the production of 2'-amino-2'-deoxy-kanamycin according to the present invention, as compared to when the parent strain 0-4-1 of *Streptomyces kanamyceticus* is cultivated in a culture medium.

In these tests, the cultivation of the parent strain 0-4-1 and the mutants A-4-6, 3AG, 18-8 and 19-2 of *Streptomyces kanamyceticus* was carried out at 28° C. for 150 hours in the same manner as in example 1 using similar jar fermentors and the culture media of the same composition, respectively. After the end of the cultivation, the resulting culture broths were assayed for the content of 2'-amino-2'-deoxy-kanamycin and of kanamycin A. The results of assay are shown in table 5 below.

TABLE 5

Experiment No.	Strains used	Content of 2'-amino-2'-deoxy-kanamycin(mcg./ml.)	Content of kanamycin A (mcg./ml.)
60	Parent strain 0-4-1	26	2,790
2	Mutant A-4-6	430	1,970
3	Mutant 3AG	285	1,785
4	Mutant 18-8	520	1,900
65	Mutant 19-2	700	1,690

Each 15 litres of the resulting culture broths were then treated in the same manner as in example 1 so that 2'-amino-2'-deoxy-kanamycin and kanamycin A could be recovered therefrom as much as possible. Amounts of the products recovered are shown in table 6 below.

11
TABLE 6

Experiment No.	Strain used	Yield of 2'-amino-2'-deoxy-kanamycin (g)	Yield of kanamycin A (g)	5
1	Parent			
	0-0-4-1	0.12	26.8	
2	Mutant A-4-6	1.90	19.0	10
3	Mutant 3AG	1.20	15.8	
4	Mutant 18-[	2.20	17.6	
5	Mutant 19-2	3.15	16.1	

From the results as shown in table 6, it is clear that the mutants A-4-6, 3AG, 18-8 and 19-2 have the intrinsic ability to

12
produce 2'-amino-2'-deoxy-kanamycin in a remarkably higher yield than the parent, typical strain 0-4-1 of *Streptomyces kanamyceticus*.

What we claim is:

1. A process for the production of 2'-amino-2'-deoxy-kanamycin in higher yield, which comprises cultivating the mutant selected from the group consisting of mutants identified as ATCC 21259, ATCC 21260, ATCC 21261 and ATCC 21268 of *Streptomyces kanamyceticus* under aerobic conditions in a usual culture medium containing carbohydrate and nitrogenous nutrient until 2'-amino-2'-deoxy-kanamycin accumulates in a profitably large amount in the culture, and then recovering 2'-amino-2'-deoxy-kanamycin from the culture.
